Primary Examiner—Jeffrey Asch

(57) **CLAIM**

The ornamental design for an emergency dispatch console, as shown.

DESCRIPTION

FIG. 1 is a front perspective view of an emergency dispatch console.

FIG. 2 is a front elevational view of the emergency dispatch console of FIG. 1.

FIG. 3 is a back elevational view of the emergency dispatch console of FIG. 1.

FIG. 4 is a top plan view of the emergency dispatch console of FIG. 1.

FIG. 5 is a bottom plan view of the emergency dispatch console of FIG. 1.

FIG. 6 is a left side elevational view of the emergency dispatch console of FIG. 1; and,

FIG. 7 is a right side elevational view of the emergency dispatch console of FIG. 1.

Structure that is not part of the claimed design, but that shows the environment in which the design is used, is represented in the drawing by broken lines.
